UNITED STATES PATENT OFFICE.

MARTIN J. VALSVIG, OF SPOKANE, WASHINGTON, ASSIGNOR OF ONE-HALF TO JOSEPH LEE, OF SPOKANE, WASHINGTON.

CLOSURE FASTENER.

Application filed October 30, 1926. Serial No. 145,295.

My present invention relates to improvements in closure fasteners which while adapted for use with closures for various receptacles and in different ways, it is especially designed for use in fastening and sealing the top of a milk can, to prevent unauthorized access to the contents of the can, and to indicate or show that the can has been tampered with. The invention contemplates the use of a seal in combination with the closure fastener which seal may be broken at the proper time, and discarded, but the closure fastener itself is adapted for repeated use. The closure fastener is of the shackle type, and in this instance is designed to fasten the top of the milk can to one of the handles of the can, and for this purpose a specially constructed shackle or double end hook is provided. The invention consists in certain novel combinations and arrangements of parts as will hereinafter be more fully set forth and claimed.

In the accompanying drawings, I have illustrated one complete example of the physical embodiment of my invention wherein the parts are combined and arranged according to the best mode I have so far devised for the practical application of the principles of my invention.

Figure 1 is a sectional view of part of a milk can and top, with the closure fastener of my invention in use thereon;

Fig. 2 is an enlarged perspective view of the fastener detached and in locked and sealed position;

Fig. 3 is a longitudinal sectional view showing the fastener and with the released latch in open position as shown by dotted lines; and

Fig. 4 is a detail of the rack device.

In the preferred form of my invention, as illustrated in the drawings, the device is adapted for use with a milk can as indicated by the numeral 1 having a neck 2 and an outwardly flaring neck ring 3. The can top or closure is indicated as 4 and is provided with an annular bead 5 and bead wire 6, and a slot 7 is provided in the can top just below the bead wire for attachment of one end of the closure fastener. The other end of the closure fastener is attached to one of the handles as 8, as shown in Fig. 1. The closure is provided with a hook 9 at one end for engaging the can top, and at the other end another hook 10 is provided for engag-

ing around the handle 8 for the purpose of fastening and retaining the milk can top 4 in position. The fastening device is made up of two main elements or members, of which the slide plate 11 is integral with the hook 10. This plate 11 is provided with a longitudinally extending slot 12 and near one end is fashioned with a pair of side plates 13 and 14 projecting at right angles to the plane of the plate 11. In combination with the slide plate, I provide a complementary rack plate 15 with which the hook 9 is integral. This plate is located between the two side plates 13 and 14, and near one end the rack plate is provided with an integral lug 16 to slide in the slot 12 and guide the relative movement of the slide plate and rack plate when they are being adjusted. On its upper or outer face, the rack plate is fashioned with teeth 17 to form a rack and a pawl 18 for coaction with this rack is pivoted at 19 between the two side plates 13 and 14 of the main plate 11, and a spring 20 carried by the pawl is adapted to glide over the teeth 17 and hold the pawl out of engagement with these teeth except when the pawl is positively pressed into engagement with these teeth.

The pawl is engaged with the teeth by means of a latch 21 which is pivoted at 22 in the side plates 13 and 14 and this latch is fashioned at one end with a friction lug 23 which engages and coacts with the pawl 18 to lock the latter in engagement with the teeth 17.

At the free end of the latch 21 are provided two side lugs 24 having perforated ends, and adapted to swing over the opposite edges or sides of the slide members of the shackle. A wire cable 25 is passed through these perforated lugs and a seal 26 is used to fasten the ends of the wire cable together.

It will be apparent that the length of the shackle or fastener may be adjusted by relatively moving the slide plate 11 and the rack plate 15 in order to adapt the device for use with milk cans in which the distance between the handle and the slotted top varies. By turning back the latch 21 to the dotted position in Fig. 3, the pawl 18 is automatically released from the ratchet teeth 17. The two main plates 11 and 15 may be adjusted with the lug 16 sliding in the slot 12 to guide the members. The length of the

shackle is adjusted after the hooks 9 and 10 have been suspended over their supports, and after the length of the shackle has been secured the latch 21 is turned down to full line position as in the figures of drawing. The movement of the latch closes the pawl 18 against the teeth 17 of the rack plate, and the free end of the latch is held while the wire cable or cord 25 is passed between its 10 perforated lugs. Then the seal 26 is applied to lock these parts together. Thereafter, the top 4 of the can will be fastened in closed position and if it has been tampered with such condition will be indicated 15 by the condition of the seal 26. The seal may be broken, of course, by authorized parties, the latch 21 released, and the fas-

tening device then removed from the milk can for future use.

Having thus fully described my invention, 20 what I claim as new and desire to secure by Letters Patent, is:—

The combination with a slotted slide plate having an end hook, and a rack plate having a lug for coaction with the slotted slide 25 plate, and provided with an end hook, of a pair of side plates on the slide plate, a spring pressed pawl pivoted in the side plates for coaction with the rack plate, a latch pivoted in the side plate for engagement with the pawl, said latch at its free end having means for encircling the side plate and rack plate.

In testimony whereof I affix my signature.

MARTIN J. VALSVIG.
